UNITED STATES PATENT OFFICE

LE ROY ELLSWORTH PECK, OF RIVERTON, WYOMING, ASSIGNOR TO COLUMBIAN CARBON COMPANY, OF NEW YORK, N. Y., A CORPORATION OF DELAWARE

PACKING OF CARBON BLACK

Application filed June 25, 1928. Serial No. 288,266.

A great deal of difficulty has been encountered heretofore in the packing of lamp black, carbon black and similar extremely light and finely subdivided powders. They cannot be compressed by ordinary means as a large amount of occluded air or other gases is compressed at the same time and in expanding when the pressure is relieved, the powder goes back to its loose readily dusting condition.

10 Tamping is also unsatisfactory.

To reduce the volume the occluded gases have been removed by making a paste of the powder and a volatile liquid and then evaporating the liquid to leave the powder in cake form, but this involves the use of a mixing apparatus and then heat treatment to remove the liquid.

I have discovered that by delivering the material to a receiver and subjecting the receiver to the action of centrifugal force during, and if need be, after the delivery, the particles of powder will crowd closely together, thereby forcing out the air from between the particles and the powder may be brought to very compact form with very much greater weight per unit of volume and with less occluded air. This reduction in the volume for a unit of mass is of special importance in the shipment and storage of the product and reduces the dusting properties during the mixing of the product with other ingredients, but does not prevent the compact mass from being readily returned to its original light flocculent condition or its dispersion in rubber, printers ink or other compositions in which carbon black and lamp black are used so extensively.

In carrying out my invention I preferably use paper bags as the receivers into which the material, hereinafter referred to as carbon black, is packed, and I mount these bags in suitable receivers so that they are externally sustained during the delivery of the carbon black thereto, and the carbon black may be continuously delivered during the high speed rotation of the apparatus.

The material is thus packed directly in the bags and the mass of packed material will be homogeneous throughout and comparatively free of occluded gases.

In the accompanying drawings I have illustrated merely one embodiment of my invention, although it will be obvious that various changes may be made in the details of construction of the various parts within the scope of my invention as defined in the appended claims.

In these drawings:

Fig. 1 is a top plan view, a portion of the casing being shown in open position and partly broken away; and

Fig. 2 is a longitudinal section on the line 2-2 of Fig. 1.

In the construction illustrated there is provided a distributing head 10 which may be secured to a drive shaft 11 which preferably has its axis substantially vertical and driven from the lower end portion by any suitable form of driving means, not illustrated.

The head includes a central chamber 12 which is closed by a bottom wall to which the shaft 11 is secured and open at the top for the entrance of the carbon black. This distributing head has a plurality of radially extending nozzles 13, each of which communicates at its inner end with the chamber 12 so that as the head is rapidly rotated and material is delivered into the head from the upper side, the material will be delivered through the several nozzles by the action of centrifugal force. The material is delivered from these nozzles directly into containers which are preferably in the form of paper bags 14 suitable for the storage and shipment of the material. The entrance opening of each bag may be gathered around the end of the nozzle and held in place by any suitable retaining means, such for instance as springs 15 pressing resiliently against the outer surface of the nozzle and holding the edge of the bag wall against the outside of the nozzle.

For supporting the bags in horizontal position and supporting the outer surface against the pressure of the material against the inner side of the bag as well as resisting radial movement of the bags and contents under the action of centrifugal force, I provide each bag with a casing formed of two separable sections. These sections may be of approximately semi-cylindrical form with

closed outer ends and of an external size approximating that of the bag to be filled.

As shown the lower half or section 16 of each casing is secured to and carried by a U-shaped frame 17, the ends of which are secured to lugs 18 which may be secured to or formed integral with the distributing head 10. The two sections are separable on the horizontal, longitudinal plane of the axis of the bag, and the upper section 19 may be secured to the lower section by hinges 20 along one edge and suitable clamps or fasteners 21 along the opposite edge. Thus the lower half of each casing section is held rigid in respect to the distributing head, while the upper half may be swung to open position as shown at the lower part of Fig. 1 so that an empty bag may be inserted and a filled one removed.

The rotating parts may be mounted in a suitable casing or shield 22 which serves to cut down wind resistance to the rotation and also to protect the workmen in case any parts should break loose during the high speed rotation of the shaft, distributing head and bag casings.

The shaft 11 may extend through a suitable anti-friction bearing in the bottom of this casing or shield, while the top wall may have a funnel or conduit 23 projecting into or registering with the top opening of the distributing head so that the material may be delivered to the latter during the rotating of the enclosed parts.

A portion of this outside shield or casing 22 is removable to permit access to be gained to the bag casings.

As illustrated in Fig. 1 the shield or casing 22 has two normally shaped sections 24 hinged at opposite sides and each enclosing a portion of the top, bottom and peripheral walls of the shield or outer casing 22. By swinging these sections away from each other as indicated in Fig. 1 one of the bag casings will be exposed so that it may be opened. The rotatable parts may be turned a little at a time until the several bag casings are brought into such position as permits the insertion of the bags and the reclosing of the bag casings. The sections 24 may then be returned to normal position and secured together in any suitable manner as for instance by a catch 25.

The bearing shown at the lower part of Fig. 2 and which supports the shaft 11, constitutes a part of or is mounted in the main frame of the machine, and the casing 22 may be rigidly secured to this bearing or to any other suitable part of the frame of the machine so as to hold the casing in position and prevent it from rotating. The funnel or conduit 23 is secured to the casing and depends from the latter, the proportion and positioning being such that it forms a comparatively close running fit with the rotating head 10.

The driving mechanism for the shaft 11 may be such as will give a speed depending upon the extent to which it is desired to compact the material. Speeds in the neighborhood of 1000 revolutions per minute or higher may be employed.

In the construction illustrated the distributing head has six nozzles so that six of the bags may be filled at the same time, but it will, of course, be evident that a larger or smaller number may be employed.

In operation the rotatable parts may be speeded up to the desired speed and a stream of carbon black slowly delivered to the interior of the distributing head so that it will be delivered in substantially equal quantities to the several bags. Such air as enters the packer along with the carbon black may pass into the bags with the latter, but due to the centrifugal action, the particles of carbon black will force their way to the bottom of the bag, and the occluded air will find its way back out through the distributing head or between the bag walls and the nozzles, but as there is no stream of the air going in except such as is occluded with the carbon black, there will be no such outflow of air as will carry out with it any objectionable quantity of the carbon black in dust form.

The rotation may be kept up for a limited period after the delivery of powdered material ceases, if desired, to give additional compacting action.

Delivery may be continuous or intermittent and may start before or while the apparatus is speeding up.

The material will be compacted in the bags to such density that none or little of the black will flow out of the bags after rotation ceases and during the removal of the bags even though they are supported in horizontal position.

In some constructions the shield or casing 22 may be made of greater height and the frame members 17 may be pivoted to the distributing head rather than rigidly secured so that when the apparatus is at rest the frames will hang down and the bags will be in vertical rather than horizontal position.

As the apparatus starts rotating and the speed increases, centrifugal force would swing the bag containers outwardly to the horizontal position as shown in Fig. 2.

Having thus described my invention, what I claim as new and desire to secure by Letters Patent is:

1. A carbon black packing apparatus, including a distributing head mounted for rotation about a vertical axis and having an inlet at the upper end thereof, a peripherally disposed series of outlet openings, a plurality of frame members secured to said head and extending radially therefrom, and a plurality of casings each carried by a corresponding one of said frame members and

- each having an inner open end registering with a corresponding outlet of said head, each of said casings including two casing sections separable in a plane at right angles to the axis of rotation of said head for enclosing a removable carbon black receiver. 5
2. A carbon black packing apparatus including a distributing head mounted for high speed rotation about a vertical axis and having radially disposed delivery nozzles and an axially disposed inlet, a plurality of frame members secured to said head, a casing carried by each frame member for enclosing and supporting a paper bag, and means for securing the open end of each bag to the corresponding nozzle. 10
3. A carbon black packing apparatus, including a substantially cylindrical non-rotatable outer casing, a shaft mounted for high speed rotation and projecting into said casing from the bottom thereof, a distributing head secured to the upper end of said shaft and disposed within said casing, said head having an inlet opening in the top thereof and radially disposed nozzles, frame members secured to said head, bag receiving casings carried by said frame members and each including two parts hinged together, one of said parts being secured to its corresponding frame member, means on each nozzle for securing there- 20 to the end of a bag disposed within the corresponding casing, and means in the top of said outer casing for directing the carbon black into said distributing head. 25
- 35 4. An apparatus for filling bags with pul- verulent material including a vertically dis- posed shaft having a head provided with ra- dially extending outlet nozzles, said head be- ing open at the top, means associated with each nozzle for clamping to the latter the mouth of the bag to be filled, and a plurality of casings carried by said head and enclosing and supporting the bags, said casings each having a top section movable to permit in- 40 sertion and removal of said bags. 45
5. An apparatus for filling bags with pul- verulent material including a distributing head mounted for rotation about a vertical axis and having radially disposed delivery nozzles, a frame secured to said head and hav- 50 ing a plurality of bag casings opposite to and spaced from the said nozzles, and means for securing to each nozzle the mouth of the bag in the corresponding casing. 55
6. An apparatus for filling bags with pul- verulent material including a shaft mounted for high speed rotation and provided with a distributing head secured to the upper end thereof, said head having an inlet opening in the top and radially disposed nozzles, frame 60 members secured to said head, and bag receiv- 65 ing casings carried by said frame members
7. An apparatus for filling bags with pul- verulent material including a shaft mounted for high speed rotation and provided with a distributing head secured to the upper end thereof, said head having an inlet opening in the top and radially disposed nozzles, frame members secured to said head, bag receiv- 70 ing casings carried by said frame members and each including two parts hinged together, whereby bags may be inserted in and removed from said casings, and means on each nozzle independent of the corresponding casing for securing thereto the mouth of the bag within the corresponding casing. 75
8. An apparatus for filling bags with pul- verulent material including a distributing head mounted for high speed rotation about a vertical axis, said head having an inlet opening in the top thereof and radially dis- 80 posed nozzles, a plurality of casings mounted for rotation with said head and each includ- 85 ing a section rigid in respect to the corre- sponding nozzle, but spaced from the latter, a second section hinged to the first mentioned section, and means for securing to each nozzle the mouth of a bag within the corresponding casing. 90
